(57) **CLAIM**

The ornamental design for an embossed battery, as shown and described.

DESCRIPTION

FIG. 1 is a top perspective view of the ornamental design of an embossed battery housing, showing said design with dashed lines **8**, **10**, and **11** for enlarged views.

FIG. 2 is a front elevation view of the design of FIG. 1.

FIG. 3 is a top view of the design of FIG. 1.

FIG. 4 is a bottom view of the design of FIG. 1.

FIG. 5 is a left side elevation view of the design of FIG. 1.

FIG. 6 is a right side elevation view of the design of FIG. 1.

FIG. 7 is a rear elevation view of the design of FIG. 1.

FIG. 8 is an enlarged perspective view of a portion of the design of FIG. 1, showing said view with an additional dashed line **9** for a further enlarged view.

FIG. 9 is an enlarged perspective view of a portion of the design of FIGS. 1 and 1.

FIG. 10 is an enlarged perspective view of a portion of the design of FIG. 11; and,

FIG. 11 is an enlarged perspective view of a portion of the design of FIG. 1.

The broken lines shown in the drawings show portions of the embossed battery which form no part of the claimed design. The shade lines in the Figures show contour and not surface ornamentation.

1 Claim, 7 Drawing Sheets
